H. M. LIPPER

SUN VISOR

Filed August 10, 1926

INVENTOR:

HARRY M. LIPPER

BY
Meister & Fairbanks

ATTORNEYS

UNITED STATES PATENT OFFICE.

HARRY M. LIPPER, OF PHILADELPHIA, PENNSYLVANIA, ASSIGNOR TO LIPPER MANUFACTURING CO. INC., OF PHILADELPHIA, PENNSYLVANIA, A CORPORATION OF PENNSYLVANIA.

SUN VISOR.

Application filed August 10, 1926. Serial No. 128,351.

My invention relates to a new and useful sun visor, and it relates more particularly to a sun visor mounted upon, and supported in position upon the forehead, by an elastic netting adapted to retain in place the hair upon the head of the wearer.

A handicap frequently encountered in outdoor sports, is the direct rays of the sun upon the players' eyes, hindering vision and 10 observation. For this reason it is the common practice among players of outdoor sports, to employ caps with visors or sun visors secured to the forehead by various means. One of the greatest sources of annoyance, discomfort and handicap, moreover, while engaged in outdoor sports, is the displacement and derangement of the hair, and the flying of the hair loosely upon the head of the player. This source of 15 annoyance, discomfort and handicap, is particularly pronounced in the case of feminine players. Various means have been resorted to, for preventing the derangement and flying of the hair of the player, and to 20 confine the same in some orderly manner.

By my present invention, I provide, in a single device, novel means, not only for shielding the eyes of a player from the rays of the sun, but also for preventing the hair 30 of the player from flying loosely and means to maintain the same in an orderly manner, without any discomfort to the wearer.

With the above ends in view, my invention consists of a novel knitted netting, having 35 a relatively wide and closely knitted head band along the front edge thereof, and having a relatively narrow reinforcing rib along the opposed or rear edge thereof, a suitable band or elastic cord extending 40 through the reinforced rear edge thereof for drawing the front head band and netting snugly onto the head of the wearer, and a suitable, relatively rigid translucent or opaque visor member permanently affixed to the front head band portion, thereby 45 rigidly supporting the same upon the forehead, in a shielding position, while the hair is at the same time neatly and comfortably confined within the netting.

50 For the purpose of illustrating my invention, I have shown in the accompanying drawings, forms thereof, which are at present preferred by me, since they will give in

practice satisfactory and reliable results, although it is to be understood that the various instrumentalities of which my invention consists can be variously arranged and organized and that my invention is not limited to the precise arrangement and organization of these instrumentalities, as 55 60 herein shown and described:

Referring to the drawings:

Figure 1 represents a perspective view of a novel sun visor embodying my invention, shown mounted in position.

Figure 2 represents a side elevation of the same.

Figure 3 represents a top plan view of the front portion the novel device of my invention, shown in a flat condition, and 70 with portion of the elastic netting broken away.

Figure 4 represents a section on line 4—4 of Figure 3, illustrating the manner in which the relatively rigid visor member is 75 fixed to the head band.

Figure 5 is a partial plan view, similar to that shown in Figure 3, illustrating a modified embodiment of my invention, 80 wherein an inner front sweat band is provided around the inner edge of the visor member, thereby to relieve perspiration.

Figure 6 represents a section on line 6—6 of figure 5.

Referring to the drawings, in which like 85 reference characters indicate like parts, 1 designates the head band of my novel device, formed by knitting parallel rows of chain stitches 2, connected at short intervals by parallel lines of thread 3 extending 90 transversely thereof, thereby to form a relatively closely knitted parallel band. 4 designates the hair net, also knitted of parallel rows of chain stitches 5, connected at greater intervals by parallel threads 6, and knitted 95 more loosely, and possessing greater elasticity than the head band 1. The head band 1 and the netting 4, are knitted simultaneously in rectangular form, upon any suitable circular, flat or other knitting machine, and upon the opposed edge of the netting, a slight reinforcing rib 7 is knitted, parallel to the head band, through which an elastic band 8 or other suitable cord may be drawn, thereby to draw the netting 4 snugly onto the 100 head of the wearer and to form it into suit-

able semihemispherical shape, and thereby also firmly to position the visor member on the forehead.

To the outer edge 9, of the head band 1, I secure, by means of a row of stitches 10, a suitably shaped, relatively rigid and translucent or opaque visor member 11, formed of any suitable material, such as celluloid or the like. This novel construction produces a finished article, shown particularly in Figures 1 and 2, whereby a visor 11 is supported on the forehead in the desired position with respect to the eyes of the person wearing the same, without any additional supporting means, other than the hair netting 4 and the band 1. By this novel unitary structure in a sun visor and hair netting a head apparel of two fold utility is produced, which affords great comfort and convenience to feminine players of outdoor sports, and is of particular advantage to feminine players of outdoor sports, having short or bobbed hair.

In Figures 5 and 6, I have illustrated a modified embodiment of my invention, in which the head band 1 is formed of two parallel portions, the upper portion 12, formed of the same light material as the netting 4, while the lower portion 13 is formed of a relatively heavier yarn, preferably a cotton, lisle or wool yarn, thereby producing a relatively absorbent lower edge portion, adapted to relieve the perspiration of the forehead.

In this modified construction, the visor member 11 is affixed not to the outer edge of the head band 1, as shown in Figures 1 to 4 inclusive, but is affixed to said head band, along a line intermediate of the upper portion 12 and the lower portion 13 of said head

band, by a row of stitches 14, whereby the outer portion 13 of said head band, by a row of stitches 14, whereby the outer portion 13 of said head band, droops downwardly, in a loose manner to form a free and flexible band, which fits the forehead snugly, just below the front visor member 11. This construction is of particular advantage for players of outdoor sports susceptible to perspiration.

The present invention is an improvement 50 upon the device disclosed in the U. S. Letters Patent No. 1,554,163 issued to Clarence Lipper on September 15, 1925.

It will now be apparent that I have devised a novel and useful sun visor which embodies the features of advantage enumerated above, and while I have, in the present instance, shown and described forms thereof which are at present preferred by me, since they will give in practice satisfactory and reliable results, it is to be understood that such forms are susceptible of modification in various particulars without departing from the spirit or scope of the invention or sacrificing any of its advantages.

Having thus described my invention, what I claim as new and desire to secure by Letters Patent is:—

In a device of the character stated, loosely knitted netting to extend over the head of the wearer, a closely knitted head band along the front edge thereof formed integrally therewith, and an elastic band along the rear edge of said netting to draw said head band and netting snugly onto the head of the wearer and a visor member affixed to the free front edge of said head band.

HARRY M. LIPPER.
